GEORGE B. BRAND, OF SYRACUSE, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,134,991.

Specification of Letters Patent. Patented Apr. 13, 1915.

Application filed December 6, 1909. Serial No. 531,566.

To all whom it may concern:

Be it known that I, GEORGE B. BRAND, citizen of the United States, and resident of Syracuse, in the county of Onondaga and State of New York, have invented certain new and useful Improvements in Type-Writing Machines, of which the following is a specification.

My invention relates generally stated to 10 typewriting machines and more particularly to that class known as stencil making machines, although various features of my invention are applicable to typewriting machines specifically.

15 One object of my invention is to provide a stencil making machine which is comparatively simply in construction and which is efficient in use.

Another object of my invention is to provide comparatively simply and efficient means for automatically varying the point of arrest of the carriage in its return movement to begin a line of writing.

A further object of my invention is to 25 place the automatic variation in the point of arrest of the carriage under the control of the line spacing mechanism.

A still further object of my invention is to 30 provide an efficient front-strike flat platen machine.

To the above and other ends which will 35 hereinafter appear, my invention consists in the features of construction, arrangements of parts and combinations of devices to be hereinafter described and particularly pointed out in the appended claims.

In the accompanying drawings, Figure 1 is a fragmentary side elevation with the parts in section and parts broken away of 40 one form of machine embodying my invention, the upper portion of the machine alone being shown. Fig. 2 is a plan view of the carriage with parts in section and parts broken away. Fig. 3 is a fragmentary front 45 view showing the margin stop mechanism and some of the associated parts. Fig. 4 is a detail vertical sectional view of the platen and some of the parts for supporting the platen and controlling its line spacing movements. Fig. 5 is a front elevation of the 50 platen and platen frame with a stencil plate held in place. Fig. 6 is a rear view of the platen and platen frame. Fig. 7 is a dia- 55 grammatic view of some of the parts to be hereinafter described.

The carriage and type bar mounting and the letter space control of the carriage are the same as in the Monarch machine.

The frame of the machine as far as shown comprises corner posts 1 and a top plate 2. 60 A type bar segment 3 is carried by the frame of the machine and supports type bar hangers 4 to which upwardly and rearwardly striking type bars 5 are pivoted. The type bars 5 are segmentally arranged and are 65 adapted to strike upwardly and rearwardly against the platen, and in the present instance are shown provided with needle point or faced types 5^a, such as those ordinarily used to perforate stencil plates. The type 70 bars may be actuated by the usual type actions employed in the Monarch machine.

The control of the carriage is effected by escapement mechanism which comprises a dog rocker 6 carrying feed dogs 7 and actuated from a universal bar in the usual manner operatively connected with a link 8. The feed dogs 7 coöperate with an escapement wheel 9 operatively connected with a shaft 10 adapted to rotate in a bearing 11 80 fixed to the top plate of the machine. The forward end of the shaft 10 has a feed pinion 12 fixed thereto. The feed pinion meshes with a feed rack 13 connected to arms 14 carried by the carriage. The carriage comprises a guide or traverse bar 15 having oppositely grooved rails 16 to receive anti-friction rollers 17 which are also received in oppositely grooved fixed guide rails 18. The guide rails 18 are secured to brackets 19 90 fixed to the top plate of the machine so that the carriage is mounted to travel from side to side of the machine above the top plate, being propelled in the direction of its feed by a spring drum 20 connected in the usual manner to the carriage. It will be understood that at each actuation of a key which controls a type bar 5, a movement of the dog rocker takes place to afford a letter space movement of the carriage in the direction of its feed or from right to left.

The construction thus far described constitutes parts similar to those employed in the Monarch machine and further detailed description thereof is deemed unnecessary.

The carriage in addition to the cross bar 15 comprises the usual forwardly extending end bars 21 and 22 which project from and are fixed to the cross bar 15 at the ends thereof. The usual forwardly projecting 110

2
5 lugs 23 on the rear cross bar of the carriage are spaced apart to receive arms 24 rigidly attached to the lugs 23 by pins or rivets 25. The arms 24 are off-set inwardly as indicated at 26 where they project forwardly and are arranged parallel to each other. These arms are provided with bearing openings to receive a shaft 27 which corresponds to the ordinary platen shaft in a Monarch machine, the shaft likewise being received in bearings in the end plates or bars 21 and 22. Finger wheels 28 are secured to the ends of the shaft and a line spacing wheel 29 is likewise fixed to the shaft by a screw 30 which is threaded into an opening in the hub 31 of the line spacing wheel and bears at its inner end against the shaft 27. A spring roller detent 32 bears against the teeth of the line spacing wheel to hold it 10 against accidental displacement in the line spacing position to which it is moved and to assure the proper positioning and complete movement of the wheel. The line spacing wheel corresponds to that ordinarily employed in the Monarch machine, the wheel shown in the present instance being provided with thirty teeth. The line spacing wheel is actuated by any suitable line spacing devices, those shown corresponding substantially to the line spacing devices ordinarily employed in the Monarch machine. These devices comprise a finger piece 33 fixed to a rock shaft which turns in a bearing 34 on the end plate 22 of the carriage. The rock shaft 15 is provided with a crank arm 35 co-operative with a line space pawl 36 carried by a pivoted carrying arm 37. An actuation of the finger piece 33 from left to right is effective to move the engaging nose of the line spacing pawl into co-operation with the line spacing wheel 29 and effect a single tooth line spacing movement of the wheel 29. A spring 38 restores the line spacing devices to normal positions. A gravity pawl 38^a (see Fig. 2) is pivoted on a support carried by a cross-rod 38^b. The pawl engages the flat back faces of the teeth of the line spacing wheel 29 and prevents a reverse rotation thereof.

20 25 30 35 40 45 50 55 60 65 The parallel arms 26 extend forwardly beyond the shaft 27 and are slotted vertically at 39 (see Fig. 1) to receive headed screws 40, the heads of the screws bearing against the arms 26 and the threaded ends of the screws engaging tapped openings in parallel guide members 41. These parallel guide members have rearwardly projecting ears 42 apertured to receive the shaft 27. The pin and slot connection 40—39 between the arms 26 of the guides 41 constitute means for affording an adjustment of the guides around the shaft 27 as an axis. The guides 41 are provided with vertical slots 43 which receive pins 44 in the nature of headed shouldered screws. These screws are re-

ceived at their threaded ends in the ends of a platen frame 45 and thus guide the platen frame in its vertical line spacing movements and connect the platen frame to the guides 41.

The platen frame has a rectangular central opening 46 which receives either of the flat faces 47 of the platen, said faces being formed in the present instance of felt or like material. A flat plate 48, preferably of metal, is interposed between the flat felt surfaces 47. This plate, which with the surfaces 47 constitutes the platen, is detachably connected to the platen frame by oppositely disposed fastening devices 49 and 50 which project from the rear side of the platen frame. The lowermost fastening devices 49 are in the nature of headed rivets cut away at 51, said rivets being fixed to the platen frame and the stems thereof being adapted to be received in cut-outs 52 in the lower edge of the plate 48 as indicated in Figs. 4 and 6. The upper fastening devices 50 are in the nature of screws provided with knurled heads by which they may be turned, the stems of the screws being received in threaded openings in the platen frame. The heads are cut away at 53 so that when the cut-away portions of the heads are opposite the upper edge of the plate 48, a removal of the plate may be effected and either of the felt faces 47 of the flat platen may be presented foremost for co-operation with the types. Thus when one face of the platen is worn out the platen may be turned for co-operation with the needle-faced types. When the screws 50 are turned to the positions shown in Figs. 4 and 6, the heads of the screws overlap the plate 48 and securely clamp it to the platen frame.

Sheet metal strips or clamping plates 54 extend longitudinally of the platen at the top and bottom edges thereof and overlap the upper and lower edges of the platen frame, the strips being spaced away from the platen frame to provide trough-like recesses at the top and bottom portions of the platen frame to receive a stencil plate, card or the like. The strips 54 are preferably turned to the rear side of the platen frame and are riveted thereto as indicated at 55. The stencil plates may be of the usual character, each comprising a base board frame 56 having a central rectangular opening 57 therein. A sheet of stencil paper 58 is pasted at its edges to the frame 56 so that the central portion of the stencil sheet is stretched across the rectangular opening 57 in the frame. A stencil plate may be slid into position, as shown in Fig. 5, by sliding the plate between the clamping strips 54. A stop pin 59 may be employed at one end of the platen frame to limit the sliding movement of the stencil plate into the machine. When the stencil plate is in place the rear face thereof bears against the fore-

105

110

115

120

125

130

most felt sheet 47 which constitutes the impact surface of the platen. It will thus be understood that a stencil plate or card may be slipped into place between the clamping plates 54 and is held against the front face of the platen and that the stencil paper or card will thus partake of the step-by-step feed movement of the carriage and will also partake of the line spacing movement of the platen effected in a manner which will hereinafter appear. It will also be seen that the means for holding a stencil plate in a flattened condition against the platen is independent of the platen, so that said holding means does not interfere with the removal or reversal of the platen. A collar 60 surrounds the platen shaft and is fixed thereto by a set screw 61. This collar bears against the right-hand bracket arm 26 and prevents a longitudinal shifting movement of the shaft 27 in one direction. The shaft is held against shifting movement in the opposite direction by a collar 62 formed as a hub of a disk 63, the hub being fixed to the platen shaft by a screw 64. The collar 62 bears against the left-hand bracket arm 26, thus preventing movement of the shaft 27 to the right.

Disks 65 and 66 are formed with hubs 67 secured by set screws 68 to a sleeve or hollow shaft 69 which surrounds and is supported on the shaft 27 between the bracket arms 26. A coiled spring 70 surrounds the sleeve 69 and is secured at one end to a pin 71 fixed to the left hand hub or sleeve 67. The opposite end of the spring extends rearwardly and is connected to a cross rod 72 which extends between and is riveted at its ends to the bracket arms 26, the rod forming a firm and rigid connection or brace between the bracket arms. The pressure of the spring 70 is exerted to turn the disks 65 and 66 in the direction of the arrow in Fig. 4. Each of the disks 65 and 66 is provided with a cut-out or slot 73 in the periphery thereof to receive an anti-friction roller 74 carried upon a shouldered screw 75 received at its threaded end in a tapped opening in the platen frame 45. The rollers 74 are carried about midway of the platen frame as shown in Figs. 4 and 6. The construction and arrangement of the parts are such that the peripheries of the disks 65 and 66 bear upon the end pieces of the platen frame at the rear sides at about the line of impact of the types against the platen, in order to resist any backward movement of the platen. By this construction the rotative device comprising the disks 65 and 66 and the hollow shaft or sleeve 69 is constantly maintained in interlocking connection with the platen frame and a rotative movement of the rotative device is effective to produce a rectilinear movement of the platen frame and the flat platen carried thereby.

The disk 65 is provided with a roller 76 connected to the disk by a shouldered screw 77. A forwardly extending arm 78 of a lever is fixed to a hub or sleeve 79 and is bifurcated at its forward end as at 80 to receive the anti-friction roller 76. The hub 79 is adapted to turn freely on the rod 72, and is prevented from moving longitudinally along said rod by sleeves 81 fixed to the rod by set screws 82. The lever is extended rearwardly to form a second lever arm 83 provided at its rear end with an anti-friction roller 84 mounted on a shouldered screw 85 received at its threaded end in a tapped opening in the arm 83. The roller 84 is received between two forwardly projecting pins 86 carried by a depending portion 87 of a margin stop member 88. This margin stop is pivoted on a shouldered screw 89 received at its threaded end in a tapped opening in a lug 90 formed on the cross bar 15 of the carriage. The margin stop is step shaped as shown in Fig. 3, each step 91 thereon constituting a stop face. This stop is adapted to coöperate with a margin stop 92 adjustable along a stop bar 93 pivotally mounted on upwardly projecting lugs 94 on the upper fixed carriage rail 18. The construction is such that the carriage in its movement to the right will be arrested at varying points depending on the elevation of the stop member 88. In other words, the elevation of the stop 88 determines which stop face 91 thereon will be brought into co-operation with the relatively fixed stop 92. When the stop 88 is in the lowermost position shown in Fig. 3 the uppermost stop face 91 is maintained in position to coöperate with the fixed stop 92 in order to arrest the carriage at a position where a line of writing may begin at a point corresponding to the position of the letter "H" on the stencil plate in Fig. 5. If, on the other hand, the second stop face 91 (counting from the left in Fig. 3) is the active stop face, then the carriage will be arrested in position where a line of writing may begin at a point corresponding to the position of the numeral "2" on the stencil plate in Fig. 5, and so on. Each stop face 91 from the uppermost to the lowermost determines a different position of arrest of the carriage in its movement to the right, the carriage being arrested successively nearer the middle of the machine by the different stop faces as they are successively elevated, as will hereinafter more clearly appear. It will be seen that there are five stop faces 91 provided in the present instance, one corresponding to each of the stencil characters on the stencil plate shown in Fig. 5. From what has been said it will be seen that the margin stop member 88 is operatively connected with the platen so that the position of the platen determines the elevation to which the stop 88 may be adjusted.

Thus if the platen be in the lowermost position then the uppermost stop face 91 will be in the position shown in Fig. 3 to arrest the carriage to begin a line of writing at a position corresponding to that indicated by the letter "H" in Fig. 5, whereas if the platen be in the uppermost position to write the fifth line of writing on the stencil, then the lowermost stop face 91 will be elevated to a position where it will coöperate with the stop 92 to arrest the carriage in its return movement in a position where the line of writing will begin at a position indicated by the letter "A" on the stencil plate in Fig. 5.

In order to effect an operative connection between the line spacing wheel and the platen I have provided in the disk 63 a series of engaging openings or holes 95 circularly arranged around the axis of the shaft 27, six such holes being shown in the present instance, one for every five teeth of the line spacing wheel 29. A spring pressed connecting device or locking latch or bolt 96 is received in a housing 97 fixed to the disk 66. A coiled expansion spring 98 is contained within this housing and surrounds the stem of the locking bolt 96. The spring at one end bears against the right-hand wall of the housing and at its opposite end against a collar or enlargement 99 provided on the locking bolt. The pressure of this spring is adapted to force the locking bolt to the left and to seat the left-hand end thereof in one of the openings 95 in the disk 63 as shown in Fig. 2. A head 100 is formed on the locking bolt to limit its movement in one direction and the under side of this head is bevelled for coöperation with a cam 101 formed upon the end of an arm 102 provided with a hub 103 which surrounds the cross rod 72 and is fixed thereto by a pin 104. There are preferably six holes 95 in the disk 63 which divides the thirty teeth on the line spacing wheel by five so that the locking bolt 96 may be received in a locking recess 95 at every fifth line space position at which the shaft 27 may be arrested. Otherwise expressed, the line spacing wheel has thirty teeth; the greatest number of line space distances or positions to which the platen is shifted is five; the number of teeth in the line spacing wheel should be a multiple of five and this multiple, which is six, determines the number of holes 95 in the disk 63. By this arrangement a hole 95 will always be in position to receive the locking latch or bolt 96 when it is released and the rotative device has been automatically turned back with the bolt to the initial position. The locking bolt 96 normally engages a locking recess in the disk 63 so that the line spacing wheel, shaft 27, the rotative device comprising the disks 65 and 66 and the hollow shaft 69 are locked 65 to rotate together and the platen is normally

connected to be moved by the line spacing mechanism and the stepped stop 88 is normally in position to be moved during the actuation of the line spacing mechanism.

I have provided an adjustable stop device 70 to limit the return movement of the platen and the devices by which said return movement is effected. Thus from an inspection of Figs. 2 and 4 it will be seen that an eccentric stop 105 surrounds the housing 97 75 and is rotatively adjusted around the housing, a screw 106 being received in a tapped opening in the eccentric and bearing at its inner end against the housing to hold the eccentric in its adjusted position. This eccentric stop co-acts with the left-hand-guide 41 as shown in Fig. 4 to limit the rotative movement of the rotative device in the direction of the arrow and thus arrest the platen controlled thereby in its initial or 85 first writing line position.

In the operation of the device the stencil sheet or plate is inserted between the clamping strips 54 as shown in Fig. 5 when the platen is in the lowermost position indicated 90 in Figs. 1 and 4. At this time the stop 88 is in the position shown in Fig. 3 where the carriage will be arrested in its movement to the right in a position so the first line of writing or stenciling will begin at the position indicated by the letter "H" in Fig. 5. The operator proceeds to write this line and after it is completed the finger piece 33 is actuated to effect the turning movement of the line spacing wheel in the direction of the arrow in Fig. 2. At the same time a return movement of the carriage to the right is effected. The actuation of the line spacing mechanism is effective to turn the shaft 27, the disk 63 and the rotative device which is 105 locked thereto. This movement effects an upward straight line movement of the flat platen one line space. A corresponding oscillation of the lever arms 78 and 83 is effected by reason of the connection of the arm 110 78 with the disk 65. This produces an upward movement of the margin stop 83 to bring the second stop face 91 to a position where it will co-act with the stop 92. These movements are produced at the first portion 115 of the return movement of the carriage so that the active stop face 91 is in a position to co-act with the fixed margin stop 92 when the carriage reaches the position of arrest. The operator proceeds to write a second line and in a like manner the fourth and fifth lines may be written, each line being started at a point progressively nearer the right-hand end of the stencil sheet as the writing proceeds.

It will be understood that the stencil sheets or plates are usually employed in addressing machines and that addresses are variously written. They seldom if ever occupy more than five lines which I have pro-

vided for in the present construction. Below I have given various styles in which the addresses are usually written.

HULL
ENGLAND

20 It will be understood that by the present construction addresses may be written in various styles as indicated above by way of illustration, and that each line is off-set automatically, the change of the carriage arresting means or margin stop mechanism being automatically effected by the line spacing mechanism. When the last or fifth line of the address, say in the last example given 25 above, has been written or produced upon the stencil sheet, the parts are so arranged and timed that the next actuation of the finger piece 33 is effective to bring the head of the locking bolt 96 into engagement with 30 the cam 101 at the first portion of the line spacing movement and the cam is effective to withdraw the locking bolt from engagement with the disk 63. This disengagement takes place during the fifth line spacing movement 35 of the platen represented in the diagram in Fig. 7 by the movement of the part 74 from the position shown at *a* to that indicated at *b*. As soon as the disengagement of the bolt 96 has been effected the spring 70 40 becomes effective to turn the hollow shaft 69 in the direction of the arrow in Fig. 2 independently of the line spacing mechanism and to effect a like turning movement of the disks 65 and 66 connected to the shaft 69.

45 This rotary movement is effective to move the platen down to the initial or first writing line position and is likewise effective to lower the margin stop 88 to the lowermost position shown in Fig. 3 so that before the 50 carriage is restored to the right the margin stop 88 will be automatically set to arrest the carriage in a position where the first line of writing may begin at a position corresponding to that indicated by the letter "H" 55 on the stencil plate in Fig. 5. The parts are thus automatically re-set to begin the writing or preparation of a new stencil plate. The stencil plate which has been produced 60 may be removed, a new stencil plate may 65 then be inserted and the preparation of the

stencil plate proceed as before. If only two, three or four lines are to be written on the sheet either of the finger wheels 28 may be employed to complete the movements of the parts by a single turning movement of a 70 finger wheel to restore them to the initial or first writing line position to begin a new stencil plate, or if desired several operations of the finger piece 33 may be effected to complete the movements of the parts necessary to restore them to the initial or first writing line position.

75 While the construction as shown is capable of handling addresses produced in most styles in common use, the operator may desire to produce addresses in other styles than those indicated. This may be done by turning the margin stop rod 93 on its pivotal support by means of the finger piece 107 or otherwise to throw the margin stop 92 out of co-operative relation with the stop 88 in order that the carriage may be spaced by hand to any position desired.

80 Any suitable stop or line lock mechanism may be employed for arresting the carriage or throwing the machine out of operation at the limit of its movement from right to left so as to prevent the platen frame from being brought into the paths of the needle-faced types.

85 While I have described my invention in connection with a machine employing needle-faced types for producing stencil sheets, it should be understood that this is but one form of typewriting machine in which the 100 invention may be embodied; that many features of the invention are applicable to a typewriting machine of the ordinary character provided with types for effecting imprints through a ribbon on a card or work 105 sheet; that many features of the invention are in no sense limited to a stencil making machine, and that some of the features of the invention may be employed without others.

110 Various changes may be made without departing from the spirit and scope of my invention.

What I claim as new and desire to secure by Letters Patent, is:—

115 1. In a front-strike stencil cutting machine, the combination of a carriage adapted to travel from side to side of the machine, escapement mechanism operative at each printing operation to afford a letter space movement of the carriage, a substantially vertically disposed flat platen carried by said carriage and mounted for substantially vertical line spacing movements on said carriage, means for holding a stencil sheet in a flattened condition on said platen for step-by-step letter space movements with the carriage and for line spacing movements with the platen, hand actuated means operable at will for effecting vertical line spac- 130

ing movements of the platen in one direction, and automatically operating means controlled by the line spacing means for bringing about a movement of the platen in 5 the opposite direction to normal or initial position:

2. The combination of a carriage adapted to travel from side to side of the machine, a substantially vertically disposed flat platen carried by said carriage and mounted for substantially vertical line spacing movements on said carriage, means for holding a work sheet in a flattened condition on said platen for letter space movements with the 10 carriage and for line spacing movements with the platen, hand actuated means mounted on said carriage for effecting line spacing movements of the platen, and automatically actuated means for arresting the 15 carriage at progressively different points in the return movements of the carriage to the right.

3. In a typewriting machine, the combination of a carriage, escapement mechanism 25 for controlling the feed movement of the carriage from right to left, a platen, hand actuated line spacing mechanism mounted on said carriage, and carriage arresting means for limiting the movement of the carriage to the right, said carriage arresting 30 means being under control of said line spacing mechanism.

4. In a typewriting machine, the combination of a carriage, escapement mechanism 35 for controlling the feed movement of the carriage from right to left, a platen, hand actuated line spacing mechanism mounted on said carriage, and means for variably arresting the carriage in its movement to the right in accordance with the actuation of the line spacing mechanism.

5. In a typewriting machine, the combination of a carriage, escapement mechanism for controlling the feed movement of the carriage from right to left, a platen, hand 45 actuated line spacing mechanism mounted on said carriage, and means for arresting the carriage in its movements to the right at points which are successively nearer the 50 right-hand end of its travel, said last mentioned means being under the control of said line spacing mechanism to determine the point of arrest of the carriage in its movement to the right in accordance with 55 the line to be written.

6. In a typewriting machine, the combination of a platen, line spacing mechanism, and means controlled by the line spacing mechanism whereby the platen is automatically returned to normal position in a direction opposite to its line feed movement when a predetermined number of line spacing movements have been effected.

7. In a typewriting machine, the combination of a platen, line spacing mechanism,

and means for automatically freeing the platen from control of the line spacing mechanism after a predetermined number of line spacing movements of the platen have been effected and for moving the platen independently of said line spacing mechanism.

8. In a typewriting machine, the combination of a flat platen, line spacing mechanism for moving said platen in one direction, and means for automatically freeing the 75 platen from control of the line spacing mechanism after a predetermined number of line spacing movements of the platen have been effected and for returning the platen in the opposite direction to the initial or first writing line position.

9. The combination of a substantially vertically disposed flat platen, line spacing mechanism therefor including a line spacing wheel, and means for automatically freeing the platen from control of the line spacing wheel after a predetermined number of line spacing movements of the platen have been effected and for returning the platen to initial or first writing line position.

10. In a stencil making machine, the combination of a substantially vertically disposed flat platen, line spacing mechanism coöperative with said platen to move it upwardly at each line spacing movement, 95 means for automatically freeing the platen from control of the line spacing mechanism after a predetermined number of line spacing movements have been effected, and means for automatically returning the platen to the initial or first writing line position after the platen is freed from control of the line spacing mechanism.

11. In a stencil making machine, the combination of a carriage which travels from 105 side to side of the machine, a substantially vertically disposed flat platen carried by said carriage, line spacing mechanism carried by the carriage and coöperative with the platen to effect step-by-step upward line 110 spacing movements thereof, and means for automatically returning the platen to the lowermost or first writing line position after a predetermined number of line spacing movements have been effected.

12. In a stencil making machine, the combination of a carriage which travels from side to side of the machine, a substantially vertically disposed flat platen carried by said carriage, line spacing mechanism carried by the carriage and coöperative with the platen to effect a step-by-step upward line spacing movement thereof, means for automatically freeing the platen from control of the line spacing mechanism, and 120 means for automatically lowering the platen to the first writing line position after the platen is freed from control of the line spacing mechanism.

13. In a typewriting machine, the combi-

nation of a carriage, a platen frame, a flat platen carried by and reversible on said platen frame to present either side of the platen for co-operation with the type, line spacing mechanism for effecting line space movements of the platen, and means carried by the platen frame for holding work sheets on the platen for movement therewith irrespective of which side of the platen is presented for co-operation with the type.

14. In a typewriting machine, the combination of a carriage, a platen, line spacing mechanism therefor, margin stops, one of said stops being carried by the carriage and the other by the frame of the machine and one of said stops being a stepped stop, means for automatically elevating one of said stops to progressively greater heights to bring different steps on the stepped stop into use and thus vary the point of arrest of the carriage, and means for automatically lowering the elevated stop to its initial position.

15. In a typewriting machine, the combination of a platen, a line spacing wheel, line spacing devices co-acting with said line spacing wheel, a rotative device actuated by said line spacing wheel and operative to move the platen, automatically actuated means for disconnecting the platen from said rotative device, and means for automatically returning the platen to initial position when it is disconnected from said rotative device.

16. In a typewriting machine, the combination of a flat platen, a line spacing wheel, line spacing devices co-acting with said line spacing wheel, a rotative device actuated by said line spacing wheel and operative to transmit a rectilinear line spacing movement to said platen, automatically actuated means for disconnecting the platen from said rotative device, and means for automatically returning the platen to initial or first writing line position when it is disconnected from said rotative device.

17. In a front-strike typewriting machine, the combination of a carriage, a substantially vertically disposed flat platen carried by said carriage, and movable vertically thereon, a line spacing wheel, line spacing devices co-acting with said line spacing wheel, a rotative device actuated by said line spacing wheel and operative to transmit a rectilinear vertical line spacing movement to said platen, automatically actuated means for disconnecting the platen from said rotative device, and means for automatically returning the platen to initial or first writing line position when it is disconnected from said rotative device.

18. In a typewriting machine, the combination of a platen, a line spacing wheel, line spacing devices co-acting with said line spacing wheel, a rotative device actuated by said line spacing wheel, means for operatively connecting said rotative device and platen at

different line space intervals in the relative movements between the two, and means for automatically disconnecting the platen and rotative device from each other at a predetermined point in the rotation of said rotative device.

19. In a front-strike typewriting machine, the combination of a carriage, a substantially vertically disposed flat platen carried by said carriage, a line spacing wheel, line spacing devices co-acting with said line spacing wheel, a rotative device actuated by said line spacing wheel, means for operatively connecting said rotative device and platen at different line space intervals in the relative movements between the two, means for automatically disconnecting the platen and rotative device from each other at a predetermined point in the rotation of said rotative device, and means for returning said platen to the initial or first writing line position when said platen and rotative device are disconnected.

20. In a typewriting machine, the combination of a line spacing wheel, line spacing devices for transmitting intermittent rotative movements to said line spacing wheel in one direction, a platen, and means controlled by the actuation of said line spacing devices for causing the intermittent movements of the line spacing wheel in one direction to effect movements of the platen in one direction and then bring about a movement of the platen in the opposite direction.

21. In a typewriting machine, the combination of a line spacing wheel, line spacing devices for transmitting intermittent rotative movements to said line spacing wheel in one direction, a flat platen, and means controlled by the actuation of said line spacing devices for causing the intermittent rotative movements of the line spacing wheel in one direction to effect intermittent rectilinear movements of the platen in one direction and then bring about a movement of the platen in the opposite direction.

22. In a front-strike typewriting machine, the combination of a carriage, a line spacing wheel, hand actuated line spacing devices for transmitting intermittent rotative movements to said line spacing wheel in one direction, a substantially vertically disposed flat platen carried by the carriage, and means controlled by the actuation of said line spacing devices for causing the intermittent rotative movements of the line spacing wheel in one direction to effect rectilinear movements of the platen first in one direction and then in the opposite direction.

23. In a typewriting machine, the combination of a flat platen mounted for rectilinear line spacing movement, a rotative device permanently operatively connected to said platen, a line spacing wheel, hand-actuated line spacing devices for intermittently

- turning said line spacing wheel in one direction only, means for operatively connecting said rotative device and the line spacing wheel, means for disconnecting such operative connection between the rotative device and platen, and spring means for automatically returning said platen and rotative device to initial position when such disconnection is effected.
24. In a front-strike typewriting machine, the combination of a carriage, a substantially vertically disposed flat platen mounted for rectilinear line spacing movement on said carriage, a rotative device permanently operatively connected to said platen, a line spacing wheel, hand actuated line spacing devices for intermittently turning said line spacing wheel in one direction only, means for operatively connecting said rotative device and the line spacing wheel, means for automatically disconnecting such operative connection between the rotative device and platen after a predetermined number of line spacing movements of the platen, and spring means for automatically returning said platen and rotative device to initial position when such disconnection is effected, so that the platen will be automatically returned to the first writing line position.
25. In a typewriting machine, the combination of a carriage, guides carried by said carriage, a platen frame that has a rectilinear movement in said guides, a flat platen carried by said platen frame, a spring returned rotative device positively connected with the platen frame at all times, a line spacing wheel, hand actuated line spacing devices coöperative with said line spacing wheel, a connecting device for operatively connecting said rotative device to turn with the line spacing wheel, and means for disengaging said connecting device to free the spring returned rotative device.
26. In a typewriting machine, the combination of a carriage, guides carried by said carriage, a platen frame that has a rectilinear movement in said guides, a flat platen carried by said platen frame, a spring returned rotative device positively connected with the platen frame at all times, a line spacing wheel, hand actuated line spacing devices coöperative with said line spacing wheel, a spring pressed latch for operatively connecting said rotative device to turn with the line spacing wheel and operatively connectible with said line spacing wheel at different relative rotative positions, and means for disengaging said spring-pressed latch to free the spring returned rotative device.
27. In a typewriting machine, the combination of a flat platen, line spacing mechanism comprising a line spacing wheel operatively connected with the platen, and means for breaking the operative connection between the line spacing wheel and platen to afford a return movement of the platen independently of the line spacing wheel.
28. In a typewriting machine, the combination of a flat platen, line spacing mechanism comprising a line spacing wheel operatively connected with the platen, means for automatically breaking the operative connection between the line spacing wheel and platen after a predetermined number of line spacing movements of the platen have been effected, to afford a return movement of the platen independently of the line spacing wheel.
29. In a typewriting machine, the combination of a flat platen, line spacing mechanism comprising a line spacing wheel operatively connected with the platen, the operative connections between the line spacing wheel and platen comprising a spring pressed latch, and means for releasing said latch.
30. In a typewriting machine, the combination of a carriage, a flat platen carried by the carriage, line spacing mechanism comprising a line spacing wheel operatively connected with the platen, the operative connection between the line spacing wheel and platen comprising a spring-pressed latch, and a cam in the path of said latch to automatically release the latch.
31. In a typewriting machine, the combination of a carriage, a shaft carried by said carriage, a line spacing wheel fixed to said shaft, line spacing devices coöperative with said line spacing wheel, an engaging member fixed to turn with said shaft, a rotative device adapted to turn independently of said shaft, an engaging member on said rotative device and which is adapted to co-operate with said first mentioned engaging member, a flat platen carried by said carriage and in interlocking engagement with said rotative device, and means for disconnecting said engaging members.
32. In a typewriting machine, the combination of a carriage, a shaft carried by said carriage, a line spacing wheel fixed to said shaft, line spacing devices coöperative with said line spacing wheel, a disk fixed to turn with said shaft, said disk having engaging openings, a rotative device adapted to turn independently of said shaft, a latch on said rotative device and which is adapted to be received in the engaging openings in said disk, a flat platen carried by said carriage and in interlocking engagement with said rotative device, and means for disconnecting said latch from the disk.
33. In a typewriting machine, the combination of a carriage, a shaft carried by said carriage, a line spacing wheel fixed to said shaft, line spacing devices coöperative with said line spacing wheel, an engaging mem-

ber fixed to turn with said shaft, a rotative device adapted to turn independently of said shaft, an engaging member on said rotative device and which is adapted to co-
5 operate with said first mentioned engaging member, a flat platen carried by said carriage and in interlocking engagement with said rotative device, and means for automatically disconnecting said engaging
10 means at a predetermined point in the rotation of said rotative device.

34. In a typewriting machine, the combination of a carriage, a shaft carried by said carriage, a line spacing wheel fixed to said shaft, line spacing devices coöperative with said line spacing wheel, a disk fixed to turn with said shaft, said disk having engaging openings, a rotative device adapted to turn independently of said shaft, a latch on said
15 rotative device and which is adapted to be received in the engaging openings in said disk, a flat platen carried by said carriage and in interlocking engagement with said rotative device, and means coöperative with
20 said latch at a predetermined point in the rotation of said rotative device for automatically disconnecting the latch from said disk.

35. In a typewriting machine, the combination of a carriage, a flat platen carried by said carriage, line spacing means for effecting intermittent rectilinear line space movements of the platen on the carriage, and means for variably arresting the carriage,
30 said variable carriage arresting means being under control of said line spacing means.

36. In a typewriting machine, the combination of a carriage, a flat platen, means for effecting line spacing movements thereof in one direction, means for automatically returning the platen in the opposite direction after a predetermined number of line spacing movements, and variable means for determining the beginning of a line, the variable means being under control of the means for effecting line spacing movements of the platen.

37. In a typewriting machine, the combination of a flat platen, means for effecting line spacing movements thereof in one direction, means for automatically returning the platen in the opposite direction after a predetermined number of line spacing movements, a carriage which carries said platen, and automatically actuated means for progressively arresting said carriage nearer the center of the machine in the return movements of the carriage as successive lines are written.

38. In a typewriting machine, the combination of a flat platen, means for effecting line spacing movements thereof in one direction, means for automatically returning the platen in the opposite direction after a predetermined number of line spacing move-

ments, a carriage which carries said platen, and automatically actuated means for progressively arresting said carriage nearer the center of the machine in the return movements of the carriage as successive lines are written, said carriage arresting means being under control of the means for effecting line spacing movements of the platen.

39. In a typewriting machine, the combination of a flat platen, means for effecting line spacing movements thereof in one direction, means for automatically returning the platen in the opposite direction after a predetermined number of line spacing movements, a carriage which carries said platen, and automatically actuated means for progressively arresting said carriage nearer the center of the machine in the return movements of the carriage as successive lines are written, said carriage arresting means comprising two stops, one of said stops being carried by the frame of the machine and the other by the carriage and one being a stepped stop, one of said stops being movable in unison with the platen in its line spacing and return movements.

40. In a stencil making machine, the combination of a carriage which travels from side to side of the machine, a substantially vertically disposed flat platen carried by said carriage, line spacing mechanism carried by the carriage and coöperative with the platen to effect a step-by-step upward line spacing movement thereof, means for automatically returning the platen to the lowermost or first writing line position after a predetermined number of line spacing movements have been effected, and automatically actuated means for variably arresting the carriage at successive return movements.

41. In a stencil making machine, the combination of a carriage which travels from side to side of the machine, a substantially vertically disposed flat platen carried by said carriage, line spacing mechanism carried by the carriage and coöperative with the platen to effect a step-by-step upward line spacing movement thereof, means for automatically returning the platen to the lowermost or first writing line position after a predetermined number of line spacing movements have been effected, and automatically actuated means for arresting the carriage progressively nearer the center of the machine after every upward line spacing movement of the platen, said carriage arresting means including a stop that moves in unison with the platen during the up and down movements of the latter.

42. In a typewriting machine, the combination of a carriage, a platen, a line spacing mechanism carried wholly by the carriage, margin stops, one of which is carried by the carriage and the other by the frame of the machine, and both said stops being apart

- from the line spacing mechanism, and means controlled by the line spacing mechanism for varying the position of one of said stops to vary the point of arrest of the carriage.
5. 43. In a typewriting machine, the combination of a carriage, a platen, line spacing mechanism carried wholly by the carriage, coöperative margin stops one of which stops is a stepped stop, said stops being apart from the line spacing mechanism, and means controlled by the line spacing mechanism for varying the position of one of said stops to bring different steps of the stepped stop into use to vary the point of arrest of the carriage.
10. 44. In a typewriting machine, the combination of a carriage, a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, and automatically actuated means for variably arresting the carriage in its return movement.
15. 45. In a typewriting machine, the combination of a carriage, a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, and automatically actuated means for variably arresting the carriage in its return movement, said means for variably arresting the carriage comprising a stop that is movable in unison with the platen.
20. 46. In a typewriting machine, the combination of a carriage, a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, and automatically actuated means for variably arresting the carriage in its return movement, said means for variably arresting the carriage comprising two margin stops one on the carriage and
25. the other on the frame of the machine, one of said margin stops being a stepped stop and one of said stops being movable in unison with the platen to bring different steps on the stepped stop into use.
30. 47. In a typewriting machine, the combination of a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, margin stops, and means for automatically controlling the relation between said margin stops to vary the point of arrest of the carriage.
35. 48. In a typewriting machine, the combination of a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, and automatically actuated means for arresting the carriage at variable points in its return movement, said carriage arresting means being under control of said rotative device.
40. 49. In a typewriting machine, the combination of a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, coöperative margin stops one carried by the carriage and the other carried by the frame of the machine, and means whereby one of said margin stops is placed under control of said rotative device to automatically vary the relation of the margin stops and thus automatically vary the point of arrest of the carriage by said margin stops.
45. 50. In a typewriting machine, the combination of a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, margin stops, one of which is stepped shaped and which stops are mounted for relative movement to bring different steps on the stepped shaped stop into use to automatically vary the point of arrest of the carriage, and means controlled by said rotative device for effecting such relative movement of the margin stops.
50. 51. In a typewriting machine, the combination of a platen, a line spacing wheel, line spacing devices co-acting with said line spacing wheel, a rotative device actuated by said line spacing wheel and operative to move the platen, automatically actuated means for disconnecting the platen from said rotative device, means for automatically returning the platen to initial position when it is disconnected from said rotative device, margin stops, and means for automatically controlling the relation between said margin stops to vary the point of arrest of the carriage.

- nation of a carriage, guides carried by said carriage, a platen frame that has a rectilinear movement in said guides, a flat platen carried by said platen frame, a spring returned rotative device positively connected with the platen frame at all times, a line spacing wheel, hand actuated line spacing devices coöperative with said line spacing wheel, a connecting device for operatively connecting said rotative device to turn with the line spacing wheel, means for disengaging said connecting device to free the spring returned rotative device, and automatically actuated means for arresting the carriage at variable points in its return movement, said carriage arresting means being under control of said rotative device.
52. In a typewriting machine, the combination of a carriage, guides carried by said carriage, a platen frame that has a rectilinear movement in said guides, a flat platen carried by said platen frame, a spring returned rotary device positively connected with the platen frame at all times, a line spacing wheel, hand actuated line spacing devices coöperative with said line spacing wheel, a connecting device for operatively connecting said rotative device to turn with the line spacing wheel, means for disengaging said connecting device to free the spring returned rotative device, margin stops, one of which is stepped shaped and which stops are mounted for relative movement to bring different steps on the stepped shaped stop into use to automatically vary the point of arrest of the carriage, and means controlled by said rotative device for effecting such relative movement of the margin stops.
53. In a typewriting machine, the combination of a carriage, a flat platen carried by the carriage, line spacing mechanism comprising a line spacing wheel operatively connected with the platen, the operative connections between the line spacing wheel and platen comprising a spring-pressed latch, a cam in the path of said latch to automatically release the latch, margin stops mounted for variable relative movement for arresting the carriage at variable points, and means under control of said operative connections for effecting such variable relative movement between said stops.
54. In a typewriting machine, the combination of a carriage, a flat platen movable in one direction to letter space and in another direction to line space, and means whereby the line space position of the platen determines the position of arrest of the carriage in its return movement.
55. In a typewriting machine, the combination of a carriage, a shaft carried by said carriage, a line spacing wheel fixed to said shaft, line spacing devices coöperative with said line spacing wheel, an engaging member fixed to turn with said shaft, a rotative device adapted to turn independently of said shaft, an engaging member on said rotative device and which is adapted to coöperate with said first mentioned engaging member, a flat platen carried by said carriage and in interlocking engagement with said rotative device, means for disconnecting said engaging members, and means for arresting the carriage at variable points in its return movement, said means being under control of said rotative device to automatically vary the point of arrest of the carriage.
56. In a typewriting machine, the combination of a carriage, a shaft carried by said carriage, a line spacing wheel fixed to said shaft, line spacing devices coöperative with said line spacing wheel, a rotative device adapted to turn independently of said shaft, a flat platen carried by said carriage and in interlocking engagement with said rotative device, means for operatively connecting and disconnecting said shaft and rotative device, and means for arresting the carriage at variable points in its return movement, said means being under control of said rotative device to automatically vary the point of arrest of the carriage.
57. In a typewriting machine, the combination of a work holder, means for line spacing the same upwardly, and a trip mechanism for releasing the work holder to permit it to return to normal position when said work holder has been line spaced to a predetermined extent.
58. In a typewriting machine, the combination of a work holder, line spacing devices for moving the same upwardly, latching devices operatively connecting said work holder with certain of said line spacing mechanism devices, and means for releasing said latching devices to enable the work holder to descend independently when it shall have been line spaced upwardly to a predetermined extent.
59. In a typewriting machine, the combination of a work holder, line spacing devices operatively connected thereto to move said work holder upwardly step-by-step, tripping devices for releasing said work holder, and automatically operating means for arresting the work holder at different initial positions lengthwise of its travel for each line to be written.
60. In a typewriting machine, the combination of a carriage, a work holder, a pivoted stepped stop carried thereby, a coöperating step on the frame-work, a lever for actuating said pivoted stepped stop, a disk connected to said lever, said disk being connected to said work holder, a second disk also connected to said work holder, and a line spacing mechanism releasably connected to said second disk.
61. In a typewriting machine, the combination of a carriage, a shaft carried by said carriage, a line spacing wheel fixed to said shaft, line spacing devices coöperative with said line spacing wheel, an engaging member fixed to turn with said shaft, a rotative device adapted to turn independently of said shaft, an engaging member on said rotative device and which is adapted to coöperate with said first mentioned engaging member, a flat platen carried by said carriage and in interlocking engagement with said rotative device, means for disconnecting said engaging members, and means for arresting the carriage at variable points in its return movement, said means being under control of said rotative device to automatically vary the point of arrest of the carriage.

nation of a flat platen or work holder, a pair of disks connected thereto, a pair of guides for said platen or work holder, means for moving said platen or work holder step-by-step upwardly, and means for releasing the same at the end of a predetermined upward movement.

62. In a typewriting machine, the combination of a flat platen or work holder, a pair of disks connected thereto, a pair of guides for said platen or work holder, means for moving said platen or work holder step-by-step upwardly, and means for releasing the same at the end of a predetermined upward movement, a lever connected to one of said disks, a pivoted multiple faced stop controlled by said lever, and a coöperating stop.

63. In a typewriting machine, the combination of a work holder, a pair of disks connected thereto so as to move said work holder upwardly, and a line spacing mechanism connected to said disks for turning them step-by-step.

64. In a typewriting machine, the combination of a carriage, feed mechanism for controlling the step-by-step letter feed movements of the carriage, a card receiving frame carried by the carriage and supporting the card in substantially a flat condition and in an upright position for the impact of upwardly and rearwardly striking type bars, a shaft carried by the carriage in the rear of said frame, operative connections be-

tween said shaft and frame for moving the latter upwardly with the card at line spacing operations and by a turning movement of said shaft, said operative connections including devices which project from and are adapted to turn with the shaft and which have a jointed connection with said frame, a line spacing wheel on said shaft, and hand actuated means carried by the carriage for intermittently actuating said wheel.

65. In a typewriting machine, the combination of a carriage, feed mechanism for controlling the step-by-step letter feed movements of the carriage, a card receiving carrier supporting the cards in substantially a flat condition and in an upright position for impact of upwardly and rearwardly striking type bars, hand actuated line spacing mechanism carried by the carriage for intermittently moving the carrier upwardly with the card at line space operations, and automatically operating means for rendering the line spacing mechanism ineffective to further elevate said carrier after a predetermined number of line spacing movements of the carrier have been effected.

Signed at Syracuse, in the county of Onondaga, and State of New York, this 3rd day of December A. D. 1909.

GEORGE B. BRAND.
